US00D614678S

(12) **United States Design Patent**
Jorgensen et al.

(10) **Patent No.:** **US D614,678 S**
(45) **Date of Patent:** **** Apr. 27, 2010**

(54) **DUST COLLECTION FITTING**

(75) Inventors: **Bill Jorgensen**, Lakeville, MN (US);
James Frey, Edina, MN (US); **Daniel Banasik**, Eagan, MN (US)

(73) Assignee: **Rockler Companies, Inc.**, Medina, MN (US)

(**) Term: **14 Years**

(21) Appl. No.: **29/333,221**

(22) Filed: **Mar. 4, 2009**

(51) **LOC (9) Cl.** **15-09**

(52) **U.S. Cl.** **D15/138**; D8/70

(58) **Field of Classification Search** D8/61-71,
D8/90, 363; D15/124-126, 138-140; 83/665;
451/41, 47, 56, 324, 342, 347-349, 357-360,
451/364, 388, 406, 420-423, 451, 547-549

See application file for complete search history.
